RACING GAME

Nathan M. Gelfand, North Valley Stream, N. Y., assignor to Ideal Toy Corporation, New York, N. Y., a corporation of New York

Application July 24, 1956, Serial No. 599,881

8 Claims. (Cl. 273—86)

This invention relates generally to game devices, and is particularly directed to a novel table-type racing game.

The particular embodiment of the present invention, which is illustrated in the drawings and which will be described hereinafter in greater detail, comprises generally a plurality of racing elements movable along respective lanes of a racing platform, independent conveyor means for moving each racing element, and manually actuatable projecting means for projecting pellets adapted to operate the conveyor means, so that actuation of the projecting means serves to move the racing elements.

It is a general object of the present invention to provide a game device of the type described which is highly entertaining and absorbing both for children and adults, and while serving to develop skill and dexterity, is capable of being easily operated by even relatively small children without supervision.

It is another object of the present invention to provide a game device having the advantageous characteristics mentioned in the foregoing paragraph, which is simple and durable in construction, neat and attractive in appearance, entirely safe in use, and which can be manufactured and sold at a reasonable cost.

Other objects of the present invention will become apparent upon reading the following specification and referring to the accompanying drawings, which form a material part of this disclosure.

The invention accordingly consists in the features of construction, combinations of elements, and arrangements of parts, which will be exemplified in the construction hereinafter described, and of which the scope will be indicated by the appended claims.

In the drawings:

Figure 1 is a top plan view showing a game device constructed in accordance with the present invention;

Figure 2 is a side elevational view of the game device of Figure 1, with parts broken away for clarity of understanding;

Figure 3 is a transverse sectional view taken substantially along the line 3—3 of Figure 1;

Figure 4 is a front end view, somewhat enlarged, taken from the left-hand end of Figure 2, with parts broken away for purposes of illustration;

Figure 5 is a partial sectional view taken substantially along the line 5—5 of Figure 2; and

Figure 6 is a longitudinal, sectional elevational view taken substantially along the line 6—6 of Figure 5.

Referring now more particularly to the drawings, and specifically to Figures 1—3 thereof, there is illustrated therein an elongate, slightly rearwardly inclined racing platform or table, generally designated 10, which is supported adjacent its rear end by a depending strut or leg 11, and supported at its front end by a depending housing structure, generally designated 12.

The platform 10 includes an elongate, generally oval-shaped pan 15 formed with a plurality of longitudinally extending, generally parallel spaced, through slots 16,

2

two being shown in the illustrated embodiment and each defining a racing lane. The platform 10 also includes an elongate bed member 18 extending longitudinally along and secured fast to the underside of the pan 15, as by fasteners 19. The bed member 18 is formed with a plurality of longitudinally extending, upwardly opening channels, troughs or grooves 19 each disposed directly beneath one of the slots 16. The troughs 19 are each formed with a relatively wide upper portion 20 having its lower wall defined by a pair of laterally spaced upwardly facing shoulders 21, and a relatively narrow lower portion 22 opening upward between the shoulders. As best seen in Figures 1 and 2, the grooves or troughs 19 open downward through the bed 18, as at 23, adjacent to their rear ends. Depending from the underside of the bed 18, adjacent to the openings 23, are a pair of laterally spaced lugs 24 to which the strut or stand 11 may be attached.

Mounted for movement longitudinally along each of the slots 16 is a racing element 27, which may assume the configuration of a rearwardly facing wheeled vehicle and driver, as illustrated, or other desired form. Each racing element includes a strut 28 depending from the vehicle through the respective slot 16 and carrying on its lower end a base member 29. Each base member is generally plate-like and rests slidably on the shoulders 21 of the respective trough 19. At the forward end of each base member 29, adjacent to the rear of the platform, may be provided a guide toe 30 projecting angularly downward into the lower trough portion 22; and, a pin or lug 31 depends from the rear portion of each base plate 29 into the lower trough portion, for reasons appearing presently. Extending transversely across the lower portion 22 of each trough 19, and fixedly secured therein, adjacent to the opening 23, is a generally horizontal pin 33. A signal piece 35 is located adjacent to the rear end of each slot 16, and includes a flag or display portion 36 disposed above the bottom wall of the pan 15, and an angularly projecting arm 37 extending generally downward into the adjacent pan slot 16 and pivotally mounted therein by a generally horizontal pin 38 extending laterally across the upper portion of the trough 19 and fixed in the bed 18. As will be noted in Figure 2, the depending arm 37 of each signal piece 35 is formed with an angulate end extension or toe 39 declining forward, to the left in Figure 2, when the flag portion 36 is in its solid-line, down position. Upon forward movement of the racing element 27, toward the rear of the platform 10, the base piece extension or toe 30 will engage with the angulate signal piece extension 39 to depress the latter and swing the signal piece to its up position shown in dot-and-dash outline.

Fixedly secured to the bed 18, at the forward end of the latter, is the housing 12 which is formed with a plurality of laterally spaced chambers 42, each depending from the forward end of the bed member 18 in alignment with a respective bed member trough 19. Further, as seen in Figures 5 and 6, each chamber 42 opens rearward adjacent its upper end into the respective bed trough. The chambers 42 each has its forward side closed by a wall 43 which walls are substantially flat and coplanar, being disposed generally upright, but inclined somewhat forward. Further, each wall 43 is formed with a generally vertically disposed through slot 44, which slots are located in adjacent spaced relation with respect to each other.

A bottom wall 45 extends forward and downward from the lower edges of the walls 43, substantially normal to the latter walls, for engagement with a floor or other supporting surface. A rearwardly concave, front shell 46, preferably fabricated of transparent material, is secured to the housing walls 43 and 45; and, a generally

vertically disposed partition 47 extends between and is secured to the shell 46 and housing walls 43, being located between the slots 44 of the housing walls. Thus, the front shell 46 and partition 47 combine with the generally flat, coplanar housing walls 43 and bottom wall 45 to define a pair of casings 48, as will appear presently in greater detail.

Mounted in each of the housing chambers 42 is a paddlewheel 49. The paddlewheels are each mounted on a generally horizontally disposed shaft 50 which extends transversely of the platform 10 and is journaled at its opposite ends in the respective chamber 42. In the illustrated embodiment, the shafts 50 are in longitudinal alignment with each other. Each paddlewheel 49 includes a hub 51 and a plurality of radially projecting paddles or spokes 52 disposed alongside of the respective hub. The paddles 52 of each wheel 49 are preferably all of substantially the same length, and arranged so as to protrude through the adjacent slot 44 into the adjacent casing 48 in their forwardly extending positions, see Figure 6. However, it may be desired to arrange the paddles 52 of each wheel 49 at various angular displacements apart from each other, for reasons appearing more fully hereinafter. It will now be understood that upon rotation of the paddlewheels 49, their paddles 52 will successively protrude through the slots 44 and into the laterally inward portions of the casings 48.

An elongate, endless, flexible conveyor element or line, which may be fabricated of string, is designated 55 and arranged in a continuous path longitudinally of and within each trough 19, preferably extending slidably, once about the respective pin 33, and extending frictionally several times about the adjacent paddlewheel drum 51. A conveyor element 55 is thus associated with each trough 19 and paddlewheel 49 for movement about its continuous path upon paddlewheel rotation. An intermediate portion of each conveyor element 55 is attached to the lug 31 of the adjacent racing element, see Figure 2, so that rotation of the paddlewheels effects sliding movement of the base plates 29, and hence of the racing elements 27 along their respective lanes.

As best seen in Figure 6, the casings 38 are disposed substantially upright, but inclined somewhat forward. Further, the shell 46 of the casings has its upper medial portion 57 depressed inwards, while the laterally opposed, lower portions of the shell are cut away or open, as at 58. Fixed to the shell 46, interiorly of each casing 48, is a generally vertically disposed guide wall 59. More specifically, each guide wall 59 is arranged in a respective casing 48 parallel to the partition 47 and on the opposite side of the paddles 52 as the partition. Also fixed to the shell 46 in each of the casings 48 is a vertically disposed, generally triangular obstruction or lug 60. As best seen in Figures 4 and 5, the lugs 60 are each arranged in substantial alignment with the lower portion of the respective paddle slot 44, while the guide walls 59 are located superior to and laterally outward of the lugs.

Located in the lower region of each casing 48 is a generally horizontally disposed resilient strip 62 which has its laterally inward end anchored in the partition wall 47 and has its outer end provided with a finger cap 63 and extends through the respective opening 58. As best seen in Figure 4, the resilient strips 62 at lower casing wall 45 are located in the lower region of their respective casings 48, below the lugs 60, but spaced, above the lower casing wall 45. Further, a pair of rest members 64 are each fixed in a respective casing 48, projecting upward from the bottom wall 45 and supporting the respective strip 62 at a point adjacent to but spaced outward from its inner, anchored end. If desired, the strips 62 may be formed as an integral piece having its intermediate portion anchored in the partition 47. It will also be noted that a spherical pellet or ball 65 is contained in each of the casings 48.

In operation, the racing elements 27 may be manually slid along their respective troughs 19 to the forward end of their respective lanes or slots 16 to start the game. The contestants or operators, two being required in use of the above-described device, will each assume a position with one finger on one of the laterally outwardly projecting caps 63. Upon depression of each finger cap 63, say to the dot-and-dash outline position of Figure 4, the supported ball 65 will be lowered. Quick release of the depressed strip 62 will serve to project the supported ball 65 upward along the side and top walls of the casing 48, for example, to the positions of dot-and-dash outlines A and B successively. Due to the forward inclination of each casing 48, the ball 65 at the solid line, rest position, and at position A, will engage with the front wall of the casing. As the front casing wall is depressed rearward in the region 27 at the ball position B, the ball is moved inward or rearward toward the wall 43. The ball then hits the partition 47, and drops generally downward between the partition and guide wall 59. In most instances, the ball 65 will fall from the position B downward into a position C in engagement with one of the paddles 52, swinging the latter downward and effecting rotation of its paddlewheel 49. However, by chance or lack of skill in the contestant, it is possible that the ball will never reach the position B, or may fall from the position B to the position D and thus avoid engaging any of the paddles 52. From the ball position C or D, the ball next rides over the obstacle lug 60 and assumes the position E substantially engaging the wall 43 and extending across the lower portion of a slot 44 to insure withdrawal of a preceding paddle 52 from the casing 48. The ball 52 then falls on the inner end of the ball-projecting strip 62 and rolls to the outer end thereof, its solid-line position in Figures 4 and 5. The casings 48 thus serve to guide the balls projected by the strips 62 toward the conveyor operating paddlewheels 49 for moving the racing elements 27. Of course, the above described procedure is duplicated in both casings 48, and repeated until one of the racing elements 27 moves into engagement with its respective signal piece 35 and swings the latter to an upstanding position to indicate a winner. Whereupon the racing elements may be manually returned to their starting, forward position and the game repeated.

From the foregoing, it is seen that the present invention provides a table-type racing game which fully accomplishes its intended objects, and is well adapted to meet practical conditions of manufacture and use.

Although the present invention has been described in some detail by way of illustration and example for purposes of clarity of understanding, it is understood that certain changes and modifications may be made within the spirit of the invention and scope of the appended claims.

What is claimed is:

1. A game device comprising an elevated racing platform provided with a plurality of longitudinally extending lanes, a plurality of racing elements mounted for independent movement longitudinally along said platform each in a respective lane, a plurality of casings fixed at one end of said platform each adjacent to a respective lane, a plurality of paddlewheels each rotatably mounted adjacent to a respective one of said casings and located so that its paddles protrude successively into the adjacent casing upon paddlewheel rotation, conveyor means operatively connected between each of said paddlewheels and its associated racing element to move the latter in response to rotation of the respective paddlewheel, a pellet freely movable in each of said casings, and independently manually actuatable projecting means in each of said casings for projecting the contained pellet against the protruding paddle of the associated paddlewheel to turn the latter, whereby said racing elements are moved along said platform by actuation of said projecting means.

each of said paddlewheels having its paddles spaced apart various angular distances so that the amount of angular turning of protruding paddles affected by said pellet will vary as successive paddles protrude.

2. A game device according to claim 1, in combination with a plurality of signal pieces pivotally mounted at the other end of said platform each adjacent to a respective lane and in the path of the associated racing element to be engaged by the latter, each of said signal pieces being shaped to be swung to an elevated position when engaged by its associated racing element.

3. A game device according to claim 1, said conveyor means comprising a plurality of endless flexible conveyor elements each arranged in a continuous path longitudinally of and below a respective lane of said platform and connected at one region to the adjacent racing element, said conveyor elements each extending about the adjacent paddlewheel for movement along its respective path upon rotation of said paddlewheel.

4. A game device comprising an elongate racing platform provided with a plurality of longitudinally extending lanes, a plurality of independent racing elements mounted for sliding movement longitudinally along said platform each in a respective lane, a plurality of paddlewheels disposed at one end of said platform each adjacent to a respective lane and mounted for independent rotation about horizontal axes extending transverse of said platform, each of said paddlewheels having its paddles spaced apart various angular distances so that the amount of angular turning of protruding paddles will vary as successive paddles protrude, a plurality of upstanding guide casings fixed relative to said platform each located adjacent to a respective paddlewheel and formed in one wall with a generally vertical slot receiving successive paddles of the adjacent paddlewheel upon rotation of the latter, conveyor means operatively connected between each of said paddlewheels and its associated racing element to move the latter in response to rotation of the respective paddlewheel, a ball freely movable in each of said guide casings, and independently manually actuatable projecting means in each of said casings for projecting the contained ball against the protruding paddle of the associated paddlewheel to turn the latter, whereby said racing elements are moved along said platform by actuation of said projecting means.

5. A game device according to claim 4, said conveyor means comprising a plurality of flexible endless lines each arranged in a continuous path longitudinally of and below a respective lane of said platform and connected

50

at one region to the associated racing element, said conveyor lines each extending about the adjacent paddlewheel for movement along its respective path upon rotation of the said wheel.

5 6. A game device according to claim 4, said projecting means comprising a resilient strip arranged generally horizontally in the lower region of each casing below said slot for supporting said ball in said casing, each of said strips having one end anchored in its respective casing and having its other end extending loosely through and out of its casing for manual depression by an operator, whereby release of said other strip end serves to project the supported ball in said casing to be guided by the latter.

10 15. 7. A game device according to claim 4, in combination with a plurality of signal pieces pivotally mounted at the other end of said platform each adjacent to a respective lane and in the path of the respective racing element to be engaged by the latter, said signal pieces 20 being shaped to be swung to an elevated position by engagement with said racing elements to indicate the termination of a race.

8. A game device comprising a racing platform having a plurality of racing elements movable independently 25 along the same, casings on said platform one for each of said elements, a paddlewheel for each of said elements having paddles spaced thereon at unequal angular distances for successive protrusion into the casing of its respective racing element, conveyor means connecting 30 each of said paddle wheels with its respective racing element to move the latter in response to rotation of the former, a pellet movable in each casing, and means independent to each casing for cooperation with the pellet for independent movement of the same in the casing 35 against the protruding paddle of the respective paddlewheel to rotate the same and to move its respective conveyor means and racing element.
